[57] CLAIM

The ornamental design for a clamp with neck and telephone holder with side wall, as shown and described.

DESCRIPTION

FIG. 1 is a perspective view of the clamp with neck and telephone holder with side wall;

FIG. 2 is a left end view of the clamp with neck and telephone holder with side wall shown in FIG. 1;

FIG. 3 is a right end view of the clamp with neck and telephone holder with side wall shown in FIG. 2;

FIG. 4 is a right side view of the clamp with neck and telephone holder with side wall shown in FIG. 1;

FIG. 5 is a left side view of the clamp with neck and telephone holder with side wall shown in FIG. 1;

FIG. 6 is a top view of the clamp with neck and telephone holder with side wall shown in FIG. 1; and,

FIG. 7 is a bottom view of the clamp with neck and telephone holder with side wall shown in FIG. 1.

The patterned surface treatment schematically depicted throughout the views is continuous about the surfaces on which it is shown. The neck is shown broken away and connected by broken lines to indicate an indeterminate length. The broken line showing of a tubular member is for illustrative purposes only and forms no part of the claimed design.
